United States Patent Office.

MICHAEL J. LOURRENTZ, OF LEAVENWORTH, KANSAS, ASSIGNOR
TO HIMSELF AND JOHN MYERS, JR., OF SAME PLACE.

Letters Patent No. 83,391, dated October 27, 1868; antedated October 17, 1868.

IMPROVED LAMP-CHIMNEY CLEANER.

The Schedule referred to in these Letters Patent and making part of the same.

To all whom it may concern:

Be it known that I, MICHAEL J. LOURRENTZ, of Leavenworth, in the county of Leavenworth, and State of Kansas, have invented a new and improved Lamp-Chimney Cleaner; and I do hereby declare that the following is a full, clear, and exact description thereof, which will enable those skilled in the art to make and use the same; reference being had to the accompanying drawings, forming part of this specification.

This invention relates to a new and simple method of cleaning the chimneys of lamps.

And it consists in combining two wires or rods, with buttons or heads thereon, in the manner hereinafter described.

The drawing—

Figure 1, represents a longitudinal section of the instrument, showing the buttons, and the manner of construction.

Figure 2 is a cross-section through the line xx of fig. 1.

Similar letters of reference indicate corresponding parts.

The instrument is formed of two wires or rods, with buttons or heads on each end of each rod.

A A' represent the rods or wires, and
B B', the buttons or heads.

The wires or rods are connected together by passing through the inner heads, as seen in the drawing, so

that the heads B' form guides for the rods, and allow them to slide freely back and forth.

In this manner a piece of cloth or paper, or other material, may be wound around the wires A, at either end, and held as a wiper between the heads, for cleaning the inside of lamp-chimneys, while the buttons at the other end would allow of a good hold for operating with the swab or wiper.

The buttons or heads may be simple disks of metal or other material, or the ends of the wire rods may be turned, bent, or coiled, so as to hold the cloth or wiper between them when they are slipped together, suitable provision being made for uniting the rods, so as to allow them to slide freely to form the grip for holding the cloth.

Having thus described my invention,
I claim as new, and desire to secure by Letters Patent—

As a new article of manufacture, the holder for lamp-chimney cleaners, consisting of the two rods A A', each double-headed, the rod A passing through the button at the inner end of rod A', and *vice versa*, whereby the cleansing-material is held between the inner head of one rod and the outer head of the other, as herein shown and described.
